UNITED STATES PATENT OFFICE.

WILLIAM L. BARTH, OF BATTLECREEK, MICHIGAN.

AUTOMATIC RELEASING DEVICE FOR BURIAL APPARATUS.

SPECIFICATION forming part of Letters Patent No. 710,406, dated October 7, 1902.

Application filed June 26, 1900. Serial No. 21,694. (No model.)

To all whom it may concern:

Be it known that I, WILLIAM L. BARTH, a citizen of the United States, residing at the city of Battlecreek, in the county of Calhoun 5 and State of Michigan, have invented certain new and useful Improvements in Automatic Releasing Devices for Burial Apparatus, of which the following is a specification.

This invention relates to improvements in 10 detachable fastenings for the bands or cords of burial apparatus. It is intended more particularly for such detachable fastenings in use with a machine for the purpose of lowering coffins or caskets; but it may be used in 15 connection with straps or cords where a coffin or casket is lowered by hand.

The object of this invention is to provide a 20 convenient, simple, strong, and safe automatically-detachable fastening device for the bands or cords used to lower coffins or caskets into a grave.

A further object is to provide such a device 25 the members of which shall be very securely coupled until the cords or straps are entirely slack and the fastening has dropped down away from the bottom of the casket or other load.

A still further object is to provide an improved latch-lever connection which shall 30 remain securely coupled until the load is wholly released.

Still further objects will appear in the detailed description to follow.

I accomplish the objects of my invention 35 by the devices and means described in this specification.

The invention is clearly defined and pointed out in the claims.

A structure embodying the features of my 40 invention is fully illustrated in the accompanying drawings, forming a part of this specification, in which—

Figure 1 is a detail plan view of my improved fastening as it appears when locked together. Fig. 2 is a detail sectional view of 45 the same, taken on line 22 of Fig. 1, it being shown in operative position in connection with a box or casket. Fig. 3 is a side elevation view of the same after the load has been

relieved and the cords or straps slackened, 50 showing the position of the parts when they automatically release.

In the drawings the sectional view is taken looking in the direction of the little arrows at the end of the section-line, and similar letters 55 of reference refer to similar parts throughout the several views.

Referring to the lettered parts of the drawings, D D' represent lowering straps or cords. To the strap D' is secured a suitable loop A, 60 the front or engaging portion of which is at right angles to the direction of the strap. The said engaging portion is preferably narrower than the strap, particularly if it is a broad strap, as is illustrated in Fig. 1. To 65 the opposite strap D is secured the opposite member B of the fastener, the engaging portion B' of which is formed something like a hook, with a downwardly and forwardly extending portion B''. A small pivoted latch 70 C is provided for closing up on the engaging portion of the loop A. A flattened lever portion C' of the latch extends upwardly and rearwardly to contact with the under side of the box or coffin E to hold the loop A securely 75 in position. This latch is pivoted at e on the main hook portion B'. It will thus be seen that when the hook is in the operative position it is, in effect, a mousing-hook, the mousing being held automatically in position by the 80 action of the load on the pivoted latch no matter what the load may be.

It will be observed in operation that when the load is lowered to a suitable support and a space left beneath for my improved fastening to drop down that as the latch is light the loop A will drop out of the hook B' and then can be easily withdrawn under the finger portion B'', which, as I have before stated, points downwardly and forwardly for this 90 purpose. It will thus be seen that when the load is lowered my improved fastening will become automatically disengaged, when each portion can be withdrawn, the rounded portion of the latch permitting it to move a little backward, when it will drop down against the shank of the hook B and will not engage any part where it may be passing. I desire

to remark in this connection that my improved fastening device can be greatly varied in its form without departing from my invention. A different form of latch might be provided, and other variations will be apparent to those skilled in the art to which my invention pertains.

Having thus described my invention, what I claim as new, and desire to secure by Letters 10 Patent, is—

1. In an automatic releasing device, the combination of a loop member A; an opposite member B having a hook-shaped engaging portion and a downwardly and forwardly 15 projecting portion beyond said engaging portion to hold it in an elevated position; and a

pivoted latch adapted to contact with the load for retaining said loop in position, as specified.

2. In an automatic releasing device, the combination of a loop; a member having a 20 downwardly-projecting engaging portion extended into a downwardly and forwardly projecting portion; and means of retaining the loop in engagement with said engaging portion, for the purpose specified. 25

In witness whereof I have hereunto set my hand and seal in the presence of two witnesses.

WILLIAM L. BARTH. [L. S.]
